US00D626137S

(12) **United States Design Patent**
McLaughlin et al.

(10) **Patent No.:** US D626,137 S
(45) **Date of Patent:** ** Oct. 26, 2010

(54) **USER INTERFACE FOR A DISPLAY SCREEN**

(75) Inventors: **Joseph McLaughlin**, Seattle, WA (US); **Michael Kruzeniski**, Seattle, WA (US); **Sean Lazo**, Seattle, WA (US); **Christina Egonis**, Seattle, WA (US)

(73) Assignee: **Microsoft Corporation**, Redmond, WA (US)

(**) Term: **14 Years**

(21) Appl. No.: **29/355,204**

(22) Filed: **Feb. 4, 2010**

(51) **LOC (9) Cl.** 32-00

(52) **U.S. Cl.** D14/486

(58) **Field of Classification Search** D14/485-495; 715/700-867

See application file for complete search history.

(57) **CLAIM**

The ornamental design for a user interface for a display screen, as shown and described.

DESCRIPTION

The FIGURE is a front view of a user interface for a display screen showing the new design.

The broken line showing of the display screen and the broken line showing of the portions of the user interface are included for the purpose of illustrating unclaimed environment and form no part of the claimed design.

1 Claim, 1 Drawing Sheet
